HAROLD L. LEVIN, OF NUTLEY, NEW JERSEY, ASSIGNOR TO THE FLINTKOTE COMPANY, OF BOSTON, MASSACHUSETTS, A CORPORATION OF MASSACHUSETTS

LAMINATED FLOORING

Application filed August 24, 1928. Serial No. 301,893.

This invention relates to an improved form of flooring or the like made from a laminated structure having a wear surface composed of individual tile or tile-like elements, or of material treated so as to simulate the appearance of individual tiles.

My invention has for one of its objects the provision of flooring material constructed of a base or foundation having superposed thereon and affixed thereto a layer of tiles or tile-like elements, or material finished so as to give an appearance of individual tiles, the foundation layer being relatively large in comparison to the size of the tiles so as to accommodate a great many tiles to thereby facilitate the rapid laying of the tiles on the floor or other structure.

Another object of my invention resides in the provision of laminated flooring units constructed as indicated, of individual tiles or material simulating the same, associated with a foundation layer in such a way that when the unit is placed in proper position on a floor in assembled relation with other similar units, the joints between the foundation material of adjoining units will be staggered with reference to the joints between the tiles of the juxtaposed units.

Other objects and advantageous features of my invention will more readily appear from the following description and an inspection of the accompanying drawings in which:

Figure 1 shows in plan one embodiment of my invention,

Figure 2 is an edge view of the unit shown in Figure 1,

Figure 3 shows a section of floor laid with units embodying my invention and illustrating the manner of joining additional units to a previously laid section of flooring, and

Figure 4 is a sectional view of a number of the units in their assembled relationship.

In accordance with my invention in one of its embodiments, I construct units to be laid in assembled relation with each other, each unit comprising a base or foundation layer to one face of which a number of individual tiles or tile-like elements may be secured.

Referring in detail to the drawings, the numeral 10 represents the base or foundation

layer which may be of any suitable material, and preferably more or less flexible, such as felt, burlap, or similar fibrous material, water-proofed if desired, in any convenient manner. The base or foundation may be formed in any suitable shape such as the rectangular configuration shown in the drawings. The tiles or tile-like elements composing the wear or tread surface of the flooring may be of any desired material such as felt saturated with asphalt or other waterproofing medium and surfaced with the usual linseed or other oil paint coating. Instead of felt base tiles, I may employ tiles of rubber or rubber composition of any of the varieties now available. Where a cheaper type of flooring is desired, the tiles may be cut from the ordinary asphalt saturated and coated roofing felt of the type surfaced with comminuted mineral matter.

The individual tile elements, of whatever nature they may be, are adhesively united with the base or foundation 10 by the use of any suitable cement or adhesive agent.

In Figure 1, I have illustrated a series of tile elements 11 and a series of similar elements 12, which, however, may be of different ornamental appearance than the tiles 11 so as to produce in the completed unit a mottled appearance such as is sometimes desirable.

It will be seen that by affixing a large number of these tiles to the base or foundation during the course of manufacture and assembling the units thus formed when laying the floor, the time required for laying the floor composed of individual tiles can be greatly decreased, since all that is required is to assemble the comparatively large units.

In carrying out my invention I prefer to arrange the tiles on the foundation layer in such a way that when a number of these large units are assembled in place, the joints between the tiles of adjoining units will be out of line with the joints between the foundation layers of the several units. In order to accomplish this result, I arrange the tiles in transverse and longitudinal rows on the base in such a way that in each alternate transverse row of tiles there is one

tile overhanging one longitudinal edge of the foundation layer, and a corresponding tile of the intervening alternate transverse rows overhanging the opposite longitudinal edge of the foundation layer. Similarly in the alternate longitudinal rows of tiles, there is a tile overhanging one of the transverse edges of the foundation with a corresponding tile in the intervening alternate longitudinal rows overhanging the opposite transverse edge of the base. Thus, as illustrated in Figure 1 the alternate transverse rows of tiles A have one tile element 13 overhanging the longitudinal edge 14 of the base 10 and the intervening rows B of tiles have a corresponding tile 15 overhanging the opposite longitudinal edge 16 of the base. Similarly in the alternate longitudinal rows C there is a tile element 17 overhanging one transverse edge 18 of the base, and corresponding elements 19 in the intervening longitudinal rows overhanging the opposite transverse edge 20 of the base. As will be seen from the drawings, the foundation is so proportioned with reference to the size of the individual tiles, that the portion of each tile extending beyond the edges of the base is substantially one half of the area of the tile. Further, at the end of each row of tiles opposite to the overhanging element of said row, no tile is affixed to the base and hence there is left at the opposite end of each row, an exposed area 21 of the base, corresponding in size and configuration to that of the overhanging or outwardly extending portions of the tile elements 13, 15, 17 and 19.

Where two sets of tiles of different appearance are employed, as illustrated in the drawings, it is preferred that the elements overhanging the base along one edge be of the one set while the elements overhanging the opposite edge of the base be of the other set so that when the units are laid the differently ornamented tiles will be in proper position, as indicated in Figure 3.

I have shown in Figure 3 a section of flooring wherein a number of units as shown in Figure 1 have been laid on the floor and joined together in proper relation, this view illustrating also the manner in which subsequent units are assembled with the previously laid section. It will be observed that the outwardly extending elements such as 15, of a previously laid section will overlap the uncovered areas 21 of the element 10a which is now being laid, while the outwardly extending tiles 13 of the unit 10a are interfitted between the units 15 and overlap the exposed areas 21a therebetween. It will be apparent, of course, that similar units may be joined to the unit 10a along its upper and lower edges as well as along its opposite longitudinal edge 16a until the floor is completely laid. If desired, the exposed marginal areas 21 and 21a that are lapped by an overhanging tile

of the adjoining unit, may have any suitable form of adhesive applied thereto so as to more firmly secure the adjoining units in place.

By arranging the tiles on the foundation layer as thus described and assembling the units thus formed in the manner set forth, the joints 22 (Figure 4) between the tiles of one unit and the adjoining tiles of the adjacent unit will always fall out of line with the joints 23 between the edges of the bases of adjoining units. This staggered relation of the joints is advantageous inasmuch as it precludes access of water, moisture, dust and the like to the substructure.

I claim as my invention:

1. As a new article of manufacture, a surface covering comprising a foundation and a wearing layer composed of a plurality of tile-like elements secured in rows to one face of said foundation, an end element of one row extending beyond the contiguous marginal edge of the foundation and the element at the opposite end of said row terminating inwardly of the opposite contiguous edge of the foundation.

2. As a new article of manufacture, a surface covering comprising a foundation and a wearing layer composed of a plurality of tile-like elements secured in rows to one face of said foundation, the end elements in alternate rows extending beyond the contiguous marginal edges of the foundation and the end elements of intervening rows terminating inwardly of said contiguous marginal edge of the foundation.

3. As a new article of manufacture, a surface covering comprising a flexible fibrous foundation and a wearing layer composed of a plurality of tile-like elements of asphalt coated felt secured in rows to one face of said foundation, the end element of one row extending beyond the contiguous marginal edge of the foundation and the element at the opposite end of said row terminating inwardly of the opposite contiguous edge of the foundation.

4. As a new article of manufacture, a surface covering comprising a flexible fibrous foundation and a wearing layer composed of a plurality of tile-like elements of asphalt coated and mineral surfaced felt secured in rows to one face of said foundation, the end elements in alternate rows extending beyond the contiguous marginal edges of the foundation and the end elements of intervening rows terminating inwardly of said contiguous marginal edge of the foundation.

HAROLD L. LEVIN.
